BOX MAKING MACHINE

Clayton Straw, Henniker, N. H., assignor to
Kingsbury & Davis Machine Company, Con-
toocook, N. H., a corporation of New Hampshire

Original application April 13, 1938, Serial No.
201,682. Divided and this application January
21, 1939, Serial No. 252,180

9 Claims. (Cl. 271—45)

This application is a division of my application Serial No. 201,682, filed April 13, 1938.

This invention relates to box-making machines in general, and in particular comprises improvements in the well-known Kingsbury & Davis paper box machine of U. S. Letters Patent No. 655,434, dated August 7, 1900, No. 728,086, dated May 12, 1903, and No. 2,082,365, dated June 1, 1937, to which documents reference can be had for an understanding of the general features of the machine and of the operation of all parts not specifically described herein. The present invention aims to improve the said machine in the way of speeding up the operation and facilitating the adjustment of the devices for feeding the blanks, from which the boxes are to be made, accurately into position beneath the reciprocating form.

In feeding the successive blanks from the supply stack one after another into position beneath the form, the prior type of pusher or "kicker" of the aforesaid patents had a purely reciprocating motion and was found to pound badly when the machine was speeded up to increase its rate of production, giving rise to improper operation as well as putting destructive strains and excessive wear on the parts themselves and their driving connections.

To avoid these drawbacks, the invention provides novel blank-feeding devices which travel in an orbit or circuitous path, instead of the previous straight-line reciprocating path, to engage and propel the successive blanks into position beneath the form, thus avoiding the arresting of the travel of the blank-pushing elements at each end of their stroke which gave rise to the pounding, vibration, and excessive wear which made it impracticable hitherto to speed up their operation. The improved type of blank-feeder preferably has the blank-pushing elements mounted on an endless chain, which by its nature operates smoothly and efficiently at all speeds attainable by the machine. Other supplemental improvements facilitating the adjustment and timing of the stroke of the blank-feeding devices, and also providing the novel feature of a yielding drive to prevent breakage by jammed box blanks, are also included in the present invention, all as shown in the accompanying drawings and set forth in the following description and claims.

An illustrative embodiment of the invention is shown in the accompanying drawings, in which,

Fig. 1 is a side elevation showing the main parts of a Kingsbury & Davis quadruple stayer,

with the improved blank-feeding devices of the invention in place thereon.

Fig. 2 is a plan view of the improved blank-feeding devices including the endless chain pusher and a portion of the feed rolls delivering blanks in succession to such pusher.

Fig. 3 is a side elevation of the parts of Fig. 2.

Fig. 4 is an end view in elevation on an enlarged scale, from the left-hand end of Fig. 3, showing details of construction of the chain and its track, several links forming the bend at the end of the chain being omitted for clarity.

Fig. 5 is a side elevation on an enlarged scale of the rubber-covered pushing rolls on the chain.

Fig. 6 is a plan view, partly broken away, of the friction-clutch drive for the chain pusher.

Through reference to Figs. 1 and 3, it will be seen that the improved blank-feeder, indicated generally by the numeral 1, is located at one end of the top of the machine, directly under the middle of the floor 236 of the hopper (of usual or any preferred construction), just as in the case of the "kicker" previously used on this machine, to receive the flat box blanks as they are fed from the stack in the hopper by feed slide 237 and feed rolls 200, 202, and to push against the middle of their rear edges to slide them along guide rails 204 into accurately centered position beneath the form 11. In accordance with the invention the rear edge of the blank is engaged by the leading one of a pair of pushers comprising rubber rollers 205, mounted on pins 208, Fig. 5, fixed in opposite ends of a link 210 of a roller sprocket chain 212 traveling in a trough 213 having a flat bottom 214, Fig. 4, and side walls 216 affixed to the bottom by screws, which side walls are undercut so that they engage the rollers of the chain and also so that in conjunction with central guide-strip 218 they overhang the side links at the under surface of the chain, preventing upward escape of the chain from the trough. This central guide-strip 218 comprises a central length of ordinary steel and two end sections of hardened steel, around the rounded ends of which latter the chain reverses its direction of travel, the rollers of the chain riding on the portion of the height of this central guide which is of greater width and thus acting as frictionless bearings at the reversing points in the chain. One or both of the end sections of the central guide are mounted for endwise adjustment to take up slack in the chain, by means of a loose key 220 received half in a groove in the bottom of such end portion and half in the bottom portion 214 of the trough,

the end portions being secured in adjusted position by cap screws 222 put through longitudinal slots in the bottom 214. The whole trough with its chain is mounted slidably in a stand 224

5 supported by legs 226 on portions of the central frame or top of the machine, lateral arms 29 of this stand also supporting the bottom 236 of the hopper which holds the blanks and the feed rolls and their bearings.

10 The trough and chain are adjusted bodily inwardly and outwardly of the machine to vary the inward travel of pusher rollers 206, by a screw 230 threaded through a lug 232 on the bottom of the outward end of the trough and rotatably mounted without axial movement in a split hub 15 234 on the outward end of hopper bottom 236 fixed at 238 to stand 224. A crank 240 is provided to turn the screw, and a clamping screw 242 turned by hand-wheel 244 clamps the split hub 234 about the shank of the screw to prevent unwanted rotation of the screw after the trough has been given its adjusted position.

15 The leading pusher roll 206 engages the middle of the outward edge of each blank as it is fed in and dropped between the upright flanges of guide-rails 204 by feed-rolls 200, 202, and pushes the blank into position against the usual stops (not shown) arresting the blank's inward travel, and the second roller 206 catches and arrests the blank if it tends to bound back as the result of being fed at high speed, the latter roll being still in position after the first one has rounded the turn; the second roller 206 is sometimes made of steel.

20 To drive the chain 212, its return run is engaged by a sprocket 246 enclosed in a housing 248 on the side of stand 224. One side of trough 213 is cut away to admit the teeth of sprocket 246, throughout a distance equalling the maximum endwise adjustment of the trough. Sprocket 246 is mounted on a vertical shaft 250, driven through a flexible coupling 252 and bevel gears 254, 256, from a horizontal jack-shaft 258, clutch 260, sprocket 262, chain 264 and sprocket 266 from countershaft 268 of the machine.

25 The blank-feeding chain 212 makes one circuit per machine cycle. Since the length of trough 213 is such that it is never necessary to adjust the inward end of the chain more than half the length of the trough inward past feed rolls 200, 202, for the longest blank the machine will take, the feed of any size of blank by the pusher is always accomplished in one-quarter of the machine cycle, which is the rest period of the form at the top of its stroke.

30 Clutch 260 serves a double purpose. It is released to permit manual setting of the chain blank-pusher to have the proper inward extent of travel and to be in proper timed relation with the particular size of blank, as the latter is delivered by the feed rolls. It also serves as a yielding drive to permit stoppage of the chain-pusher by broken-ended or jammed blanks. The casing 270 of the clutch is set-screwed and keyed to 35 jackshaft 258, and contains a series of pockets holding expanding springs 272 causing an annular metal plate 274 to grip sprocket 262, free on shaft 258, between leather washers 276, the outer one of such washers bearing against the 40 flange of a hand-nut 278 threaded onto the end of shaft 258. As the outward movement of plate 274 is limited by pins 280 having other smaller pins through their extremities outside housing 270, hand-nut 278 can be quickly backed off to 45 release sprocket 262 completely.

Lower feed roll 202 is reduced in diameter as indicated at 282 to provide clearance for the pusher rolls 206.

5 While I have illustrated and described a certain form in which the invention may be embodied, I am aware that many modifications may be made therein by any person skilled in the art, without departing from the scope of the invention as expressed in the claims. Therefore, I do not wish to be limited to the particular form 10 shown, or to the details of construction thereof, but

What I do claim is:

1. In a box-making machine, in combination, blank-feeding devices including an endless chain 15 lying wholly in planes parallel to the blank while the latter is being fed thereby, blank-propelling elements mounted thereon and traveling therewith and extending at right angles to such planes and into the plane of the fed blank, and means 20 for driving such chain.

2. In a box-making machine, in combination, blank-feeding devices including an endless chain, blank-propelling elements mounted thereon and traveling therewith, means for driving such chain, 25 and single means for moving the chain in the line of its travel bodily as a unit inwardly and outwardly of the machine.

3. In a box-making machine, in combination, blank-feeding devices including an endless chain, 30 blank-propelling elements mounted thereon and traveling therewith, means for driving such chain, means for moving the chain in the line of its travel bodily inwardly and outwardly of the machine, and means disconnectably clutching the 35 chain to its driving means to permit change of the timed relation between its blank-propelling elements and the other parts of the machine.

4. A blank-feeder for box-making machines comprising in combination, an endless chain, 40 blank-propelling means on such chain and carried thereby successively inwardly and outwardly of the machine, a guiding member on which the chain runs and having portions around which the chain reverses its direction of travel at each 45 end of its runs, and means mounting such guiding member on the machine with capacity for adjustment of the position of the guiding member inwardly and outwardly of the machine to lengthen or shorten the distance to which the blank is 50 propelled.

5. Blank-feeding devices for box-making machines having a form, including in combination a support for a stack of flat blanks, and feeding means travelling in an orbit which includes a 55 component of movement which extends from the support toward the form, propelling the blanks one by one into position beneath the form and remaining in propelling engagement with the successive blanks until its travel is at right angles 60 to that of the blanks and thereafter receding from the blanks.

6. Blank-feeding devices for box-making machines having a form, including in combination 65 a support for a stack of flat blanks, primary feeding means feeding the blanks from such stack one by one, secondary feeding means travelling in an orbit having a direction of extent from the support toward the form pushing each blank 70 from the point where it is left by the primary feeding means to final position beneath the form, and means for varying the limit of approach of the secondary means toward the form.

7. Blank-feeding devices for box-making ma- 75

chines having a reciprocating form, including in combination a support for a stack of flat blanks, a travelling pusher propelling the blanks from the support to a position beneath the form, driving means imparting a constant scope of travel to the pusher, means varying the position of the limits of travel of the pusher without changing its scope, and means disconnecting the pusher from its driving means during such varying whereby its proper timed relation to the reciprocating form is attained.

8. Blank-feeding devices for box-making machines having a reciprocating form, including in combination a support for a stack of blanks, an endless chain, a blank-engaging element carried thereby, a guide for such chain, means combined with the support for shifting the chain and its guide as a unit toward and from the reciprocating form, a sprocket propelling the chain, drive means actuating the sprocket and thus the blank-

propelling element in timed relation to the reciprocating form, and clutch means releasably connecting the sprocket and its drive means to permit bodily shift of the chain and its guide with subsequent reestablishment of the timed relation between the blank-propelling element and the reciprocating form.

9. Blank-feeding devices for box-making machines having a reciprocating form, including in combination a support for a stack of flat blanks, a traveling pusher propelling the blanks one by one from the support to a position beneath the form, and yieldable friction driving means for the pusher permitting manual change of the limit of its travel toward the form and of its operative timed relation to the form and also permitting arrest of the pusher in its course by a jammed blank without breakage or injury of parts of the machine.
